ATT'YS.

UNITED STATES PATENT OFFICE.

CHARLES D. McDONALD, OF LOS ANGELES, CALIFORNIA.

MATTRESS SUPPORT FOR FOLDABLE BEDS AND THE LIKE.

Application filed October 26, 1922. Serial No. 597,095.

To all whom it may concern:

Be it known that I, CHARLES D. McDONALD, a citizen of the United States, residing at Los Angeles, in the county of Los Angeles 5 and State of California, have invented new and useful Improvements in Mattress Supports for Foldable Beds and the like, of which the following is a specification.

This invention relates to mattress supports for foldable beds and the like, and has for an object to provide an extremely simple, practicable, substantial and yielding support for mattresses. Another object is to provide a mattress support that is adapted 10 to be readily connected to a bed frame of any suitable character, and it is also an object to provide a mattress support of flexible character and which is so constructed that one longitudinal side portion of the support may be depressed under a load without placing the remaining longitudinal portion under flexure or tension.

Other objects and advantages will be made manifest in the following specification of the 25 embodiment of the invention illustrated in the accompanying drawings, wherein:

Figure 1 is a perspective of a foldable bed frame to which the improved mattress support is attached;

Figure 2 is a plan of the frame and the attached support, a side portion of the latter being illustrated as flexed under a load;

Figure 3 is a sectional detail of the mountings and the portion of the mattress support;

Figure 4 is a cross section on the line 4-4 of Figure 2, showing the construction of the flexible support.

Fig. 5 is a section of Fig. 2 on the line

40 5-5.

Fig. 6 is a section of Fig. 2 on the line 6-6.

The mattress support of the present invention consists of a number of longitudinally extending straps 2 of any suitable material, such, for instance, as woven hemp strips. One end of each of the straps is provided with a hem or bight 3, and through the bights 3 of a parallel series of the straps 45 there is passed a substantial cross bar 4 which may be a strip of wood. Extending through the strip is a number of longitudinally spaced screws 5, the inner ends of which are provided with nuts 5^a concealed

within the bights 3 of the straps 2. The 55 screws 5 are adapted to be arranged in the end members 6 of a bed frame structure including side rails 7 which in the present case are shown as foldably jointed as at hinges 8, although it is to be understood 60 that the present mattress support may be combined with any suitable bed frame.

Each strip has also a smaller bight 3^a at one end and through this extends a flexible rod 9, preferably of wire. The wire rod 9 65 is yieldingly connected to the contiguous end members 6^a of the bed frame by a set of tension springs 10, ends of which are connected in screw eyes 11 extending inwardly from the inner face of the frame end 6^a. The opposite ends of each of the springs are provided with hooks 10', the ends of which are forced through the fabric of the strips surrounding the rod. In this manner, the tension of a load imposed upon 70 the straps is not imposed directly upon the spring hooks 10', but is transmitted directly to the wire rod 9 and this transfers the load to the spring hooks 10' and, therefore, the hooks do not tend to pull out of or tear the 75 fabric of the straps.

As clearly shown in Figure 4, the several longitudinally extending straps are sewed at their end portions in overlapping position, the longitudinal edges not being secured together. For transversely connecting the straps to prevent undue separation under a load, a suitable number of transverse fabric or other flexible ribbons 13 are stitched as at 14, Fig. 5, to the straps. The 80 longitudinal edges of the straps, between the sewed overlapping ends, are free from each other.

The tension of the longitudinal straps 2, forming the mattress support, may be readily 85 controlled by the screws 5 passing through the end bar 6 of the bed and having nuts 6^a in the bights 3.

When the support is attached to the frame by the springs 10 the ends of the frame bow in under the tension. I preferably make the central straps of the series shorter than the outer straps with the result that when the support is mounted and tightened, the central straps are under the greatest tension. The tension of the straps causes them to trough up as is shown in Fig. 5.

When a load is imposed upon one side of

the support, the troughs are flattened out without transferring any side pull to the other side of the support.

No mattress is needed, or any kind may 5 be used. The webbing is light, durable and cannot rust as metal supports do.

One of the objects is to provide a mattress support that may be rolled into a very small and compact bundle to facilitate storage 10 and transportation and occupy but little space.

As above stated, the longitudinal straps 2 are overlapped slightly marginally contiguous to the ends, but are not overlapped 15 medially of their length, and therefore when the straps are placed under tension they laterally crowd each other with the result that they assume the trough-like formation clearly shown in Fig. 4. This permits the 20 mattress support to be loaded without any tendency of the straps laterally pulling on each other, since the greater width of the intermediate portion of the straps as compared to their overlapping end portions, 25 provides sufficient excess to permit the straps to flatten without transverse tension. The load imposed on the support does not tend to pull the straps out of alinement, or in any way affect the other portions of the support.

Further embodiments, modifications and 30 variations may be resorted to within the spirit of the invention as claimed.

What is claimed is:

1. A mattress support for a bed frame consisting of a set of parallel longitudinally 35 extending flexible straps, and means along the transverse ends of the straps for attaching the same to a bed frame, the longitudinal straps being free from each other at their contiguous parallel edges, the said 40 parallel edges slightly overlapping at the end portions and being longitudinally stitched.

2. A mattress support for a bed frame consisting of a set of parallel longitudinally 45 extending flexible straps, means along the transverse ends of the straps for attaching the same to a bed frame, the longitudinal straps being free from each other at their contiguous parallel edges, the said parallel 50 edges slightly overlapping at the end portions and being longitudinally stitched, and transverse ribbons located between the ends of the straps and loosely connecting the 55 straps together.

In testimony whereof I have signed my name to this specification.

CHARLES D. McDONALD.
